UNITED STATES PATENT OFFICE.

DONALD H. REEVES, OF DAYTON, OHIO.

PUMP.

Application filed December 3, 1920. Serial No. 428,097.

To all whom it may concern:

Be it known that I, DONALD H. REEVES, citizen of the United States, residing at Dayton, in the county of Montgomery and State of Ohio, have invented certain new and useful Improvements in Pumps, of which the following is a specification.

My invention relates to mechanically operated pumps especially designed for pumping gasoline and other fluids. The pump herein-after described and illustrated is especially designed for use on an airplane to feed fuel from the main reservoir or tank to the carburetor or carburetors or to the gasoline tank from which it flows by gravity to the engine or to the carburetor thereof.

Experience has demonstrated the advantage in an airplane of a mechanically operated pump as a primary means of feeding fuel. One of the main objects of the present invention is to provide a pump which will not necessitate the use of a gland or packing joint of any kind between the fluid chamber and the operating mechanism.

A further object of the invention is to provide means for maintaining discharge pressure of a predetermined maximum without the use of any relief valve or similar device.

A further object of the invention is to provide a pump which will maintain a practically constant discharge pressure; also one which will maintain a predetermined discharge pressure in case one unit should become inoperative.

A further object in view is to provide a pump which may be made practically a part of the engine using the fluid pumped thereby, the pumping mechanism being driven by the engine.

A further object in view is to provide a pump adapted for use with a supercharger or other apparatus the use of which necessitates the maintenance of a discharge pressure of a predetermined constant amount.

With the above and other objects in view, the invention consists in the novel construction, arrangement and combination herein fully described, illustrated and claimed.

In the accompanying drawings,

Fig. 1 is a partial vertical section through the pump taken on line 1—1 of Fig. 3;

Fig. 2 is a vertical section taken in the same direction as Fig. 1, on line 2—2 of Fig. 3;

Fig. 3 is a partial vertical section on line 3—3 of Fig. 2;

Fig. 4 is a plan view of the pump;

Fig. 5 is a vertical section through the drainage chamber;

Fig. 6 is a diagrammatic view showing the combination with the pump of a drainage chamber and a supercharger.

The pump comprises a base section 1 having a flange 1^a by which it may be secured to the engine, to be driven thereby, or to any other desired support. The base section has mounted thereon a plate 2^a on which is placed the pump chamber 2. The plate 2^a has guides 3 and bearings 4 for a purpose hereinafter described. The pump chamber is permanently secured to the base section 1 by any suitable fastening means such as shown in the drawings and mounted upon the pump chamber 2 is a manifold 6 comprising an intake passage 7 and a discharge passage 8. Mounted within the pump chamber 2 are two pumps or units each of which comprises a stationary or fixed head 9 secured to the pump chamber and containing an inlet valve 10 and an outlet valve or discharge valve 11, the same being normally held against their seats so as to close the inlet and discharge ports by means of springs 12 and 13 respectively. Each cylinder head also comprises a plurality of holes 14, to permit the liquid to flow back and forth. Attached fixedly to each cylinder head 9 is a bellows 15 which is constructed wholly of thin sheet metal to provide a flexible corrugated substantially cylindrical wall which admits of longitudinal compression and expansion of the bellows as a whole. To the lower end of the bellows 15 there is fastened a dished head or flange member 16, the same being cupped or dished upwardly from the bottom thereof to form a housing for the upper portion of a compression spring 17 which acts between the head 16 and the plate 2^a at the bottom of the pump chamber.

Slidably mounted rods 18 are fixedly attached at their upper ends to the heads 16 and carry rollers 19 which are actuated in a downward direction by means of cams 20 fast on a rotary cam shaft 21. A worm wheel 22 is fixed on the cam shaft 21 and is driven by a worm 23, fast on the pump operating shaft 23^a adapted to be driven by any suitable source of power which may consist of a shaft or other part of the engine in con-

nection with which the pump is used. A drain outlet 24 is provided for draining off the contents of the pump chamber in case of leakage as will presently appear.

5 The operation of the pump is as follows:

The two pump units or bellows act alternately, one of the bellows filling while the other is discharging. The action of a single bellows or unit is as follows:

10 Starting with the parts in the position shown in Figs. 2 and 3, the bellows 15 is expanded by a source of power coming through worm 23, wormwheel 22, cam shaft 21, cam 20, roller 19, rod 18 and head 16. Simultaneously the spring 17 is compressed. The expansion of the bellows 15 draws liquid from the main reservoir through the intake passage 7, lifts the valve 10 and draws the liquid through the holes 14, filling said bellows 15. The spring 12 closes the valve 10 when the liquid ceases to flow through it in this direction. The cam 20 has now turned through 180 degrees. As the cam 20 continues to rotate to its original position, the spring 17 acting through the head 16 compresses the bellows 15, forcing the liquid through the valve 11 into the discharge passage 8 of the manifold 6 to its destination. The spring 13 closes the valve 11 when the liquid ceases to flow through it in this direction and the cycle of the pump is now complete. Constant discharge pressure is insured by the fact that the pump units discharge alternately, combined with the fact that, in case the discharge pressure is such that the springs 17 through the rods 18 hold the rollers 19 against the cams 20, bellows 15 will discharge at a uniform rate due to the shape of the cam. In case the pressure upon the discharge valve 11 exceeds or equals the pressure which the spring can produce within the bellows 15 at any time during its compression, said spring 17, of course, may act no further during this cycle.

15 It will however be fully compressed again when the cam 20 engages and depresses roller 19. In case the bellows should break or leak within the pump chamber, the drain 24 allows the liquid to flow away from and out of the pump chamber to be discharged at any desirable point.

In order to adapt the pump to the supercharging device, it is necessary to establish communication between the pump chamber and the compression side of the supercharging device shown at A and also to add a means for draining the pump chamber in case of leakage of one of the bellows. This may be accomplished in the present embodiment of my invention by connecting a tube between the drain outlet 24 and the compression side of the supercharging device, and another tube between the drain outlet 24 and a drainage chamber B illustrated in detail in Fig. 5.

The drainage chamber B comprises an outlet 26 and an inlet 27 and contains an air tight float 28 acting in conjunction with suitable guides 29 in the chamber B. At the bottom of the float 28 there is a needle valve 30 which cooperates with the seat 31 to close the outlet 26. The inlet 27 may be connected to the drain outlet 24 of the pump and also to the compression side of supercharging device as shown in the diagrammatic view Fig. 6.

The pressure exerted by the spring 17 will at all times be augmented by the pressure existing in the pumping chamber. Since this is the same as the pressure at the discharge side of the supercharger or other apparatus described above, it follows that the discharge pressure of the pump will at all times be equal to the pressure due to the spring 17 plus the pressure existing on the discharge side of the supercharger A, or other apparatus of the nature referred to. Under normal conditions, there will be no liquid in the chamber B and the pressure from the supercharging device will keep the needle valve 30 against the seat 31 and close the outlet 26. In case liquid leaks into the pump chamber 2 it will flow into the drainage chamber B and when the level of liquid attains certain height therein, the float 28 will be lifted, and therefore needle valve 30 will be opened, allowing the liquid to drain through the outlet 26.

When there is no demand on the pump and consequently no discharge from the pump, the pump bellows being filled and the spring 17 being compressed, the parts mentioned remain in such condition, while the driving shaft and cam shaft continue to rotate. This gives automatic pressure regulation.

While I have illustrated my invention in one embodiment thereof, it should be understood that the same results may be obtained in other ways and by other means within the scope of the following claims:

What I claim is:

1. In a pump, an enclosing pump chamber, two bellows contained in said chamber and having intake-and exhaust ports, means for simultaneously compressing one bellows and expanding the other bellows, a drainage chamber in communication with said pump chamber, and means for maintaining equal pressure in both of said chambers.

2. In a pump, an enclosed pump chamber having a drain outlet, two bellows contained in said chamber and each having a valved intake port and a valved discharge port communicating with the exterior of said chamber, and means for simultaneously compressing one bellows and expanding the other bellows, a drainage chamber into which said drain outlet may discharge, and means for maintaining an equal pressure in

both of said chambers greater than atmospheric pressure.

3. In a pump, an enclosed pump chamber having a drain outlet, two bellows contained in said chamber and each having a valved intake port and a valved discharge port communicating with the exterior of said chamber, and means for simultaneously compressing one bellows and expanding the

other bellows, a self-venting drainage chamber into which said drain outlet may discharge, and means for maintaining an equal pressure in both of said chambers greater than atmospheric pressure.

In testimony whereof I have affixed my ¹⁵ signature.

DONALD H. REEVES.
